J. T. SMITH

CARBOY BOX

Filed Feb. 14, 1924

UNITED STATES PATENT OFFICE.

JOHN THOMAS SMITH, OF WOBURN, MASSACHUSETTS, ASSIGNOR TO MERRIMAC CHEMICAL COMPANY, OF WOBURN, MASSACHUSETTS, A CORPORATION OF MASSACHUSETTS.

CARBOY BOX.

Application filed February 14, 1924. Serial No. 692,910.

To all whom it may concern:

Be it known that I, JOHN T. SMITH, a citizen of the United States, residing at Woburn, in the county of Middlesex and State 5 of Massachusetts, have invented certain new and useful Improvements in Carboy Boxes, of which the following is a specification.

This invention relates to a shipping case or box for fragile receptacles generally 10 known as carboys.

Among the objects of the invention is the provision of a carboy box which will efficiently support and protect the fragile receptacle or carboy and into which the carboy is readily placed and replaced, and which is of a relatively light, simple and inexpensive construction and the parts of which are readily replaced and repaired.

The accomplishment of the foregoing objects and the advantages of the carboy box of my invention will be apparent from the following detailed description thereof.

In the drawing:—

Fig. 1 is a perspective view of the box; 25 Fig. 2 is a plan view of the box with the cover removed;

Fig. 3 is a central vertical sectional view through the box;

Fig. 4 is a top plan view of the box with 30 a carboy in place in it with parts broken away to show the method of placing the carboy in the box; and

Fig. 5 is a vertical elevational view of the box and a carboy in place in it with parts 35 broken away to show the method of placing the carboy in the box.

The carboy box comprises the usual rectangular construction A of suitable dimensions to receive the carboy, that is, of sufficient cross-sectional area to leave a substantial free space between the sides of the carboy and the walls of the box and of sufficient depth to enclose the body of the carboy and permit the neck to protrude. The 40 box is provided with shoes 1 and carrying cleats 2 as is customary. The bottom 8 of the box carries a plurality of cushion members 3 arranged in a circle adapted to cushion the bottom of the carboy.

The vertical strips 4 each carry two cushion members 3, one adjacent each end, adapted to cushion the sides of the carboy. The cushions 3 carried by strips 4 are mounted thereon at an angle (see Fig. 2 of the drawing) so that their flat front faces stand tangent to the surface of the carboy at the point of contact and in order to provide ample clearance between the strips 4 and the carboy, one corner of each strip is cut away or beveled (see Fig. 2).

The cover of the box 5 has an opening for the neck of the carboy which, if desired, may be surrounded by a ring of cushion members adapted to bear downwardly against the shoulder of the carboy. This 55 however ordinarily is unnecessary and therefore is not illustrated.

The box, including the rectangular construction A, shoes 1, carrying cleats 2, bottom 8, top 5 and strips 4, preferably is made 60 of wood and of course may be made any suitable size, depending upon the size of carboy for which the box is designed. The size and number of the cushion members 3 also may be varied to suit the requirements. 65 For the sake of economy in the cost of materials and in the construction and assembling of the parts and also from the standpoint of utility I prefer to use cylindrical cushion members made of cork. These may be mounted on the bottom 8 and the strips 4 by inserting them in recesses therein and preferably securing them in place by means of glue, shellac or dowels. After the cork 70 cushions have been secured in place they may be paraffined to protect them against decay or the action of corrosive liquids, such as acids, carried in the carboy.

The rectangular construction A, the bottom 8 with its cushions 3 and the strips 4 with their cushions 3 are manufactured 75 separately and then assembled around a carboy as follows:

A bottom 8 is nailed onto a rectangular construction A, a carboy is set in place and two of the strips 4 and a right angle corner guide 6 are inserted in each corner of the box. Wedges 7 are then driven between

each edge of each guide 6 and each strip 4, forcing the cushions 3 carried by the strips 4 into contact with the carboy. The strips 4 are then secured in place by means of 5 nails driven from the outside of the box, one or more nails in each strip being inclined toward the adjacent corner of the box to prevent movement of the strips away from the carboy.

10 The wedges 7 and the guides 6 are then removed and the cover 5 nailed in place.

For replacing a broken carboy it is only necessary to remove the cover 5 and one pair of strips 4 at one corner of the box, insert 15 a new carboy and replace the two strips 4 by the use of a corner guide 6 and wedges 7 as described above.

Worn out or broken cushion members are replaced by removing the bottom 8 or a strip 20 4 carrying the defective cushion and replacing it with a new bottom or a new strip as the case may be.

The advantages of my invention with regard to the cost of material, economy in 25 the manufacture of the parts, the replacement of worn out and broken parts and the replacement of broken carboys are apparent from the foregoing description. It is noted particularly that the parts of the box including the rectangular part A, the bottom 30 8 and strips 4 with their cushion members 3 and the cover 5 are well adapted to economical mechanical production. All of the parts may be made by machine and the cushion members 3 mounted by machine. It is evident that the mounting of the cushions 3 35 on the bottom 8 and the strips 4 before they are assembled is much more simple and easier than it would be to mount the cushions on the inner walls and bottom of an otherwise completed box. It is also evident that 40 the replacement of defective cushions by removing the bottom 8 and strips 4 is much easier than it would be to remove defective 45 cushions from the inner walls and bottom of the box and secure new ones in place. After a bottom 8 or strip 4 carrying a defective cushion member has been removed from the box it may be repaired for subsequent use.

50 It is further noted that in my box construction the cushion members are firmly pressed against the walls of the carboy. This is a desirable feature which is very difficult to accomplish when the box is 55 assembled before the carboy is put in place or by applying the individual cushion members after the carboy is in place. It is further noted that in my carboy box no nails are exposed where they may come in contact 60 with the carboy.

The use of mineral or other loose packing with its attendant disadvantages is eliminated. Loose packing as is known has the disadvantage that it increases in weight by

the absorption of moisture and liquids 65 spilled on it in the use of the carboy and it is very difficult to handle in the replacement of broken carboys.

By comparison with many of the old style carboy boxes my carboy box is of comparatively light weight and requires much less lumber in its construction, thus providing a substantial saving in the cost of material and shipping charges.

I claim:

1. In a carboy box, the combination of a vertical strip carrying cushioning means in one face thereof to bear upon a carboy and means for moving the strip into the narrowing space between a side of the box and a carboy therein.

2. In a carboy box, the combination of a vertical strip carrying cushioning means in one face thereof to bear upon a carboy and means for moving the strip into the narrowing space between a side of the box and a carboy therein, said means including a wedge element.

3. In a carboy box, the combination of a vertical strip carrying cushioning means in one face thereof to bear upon a carboy and means for moving the strip into the narrowing space between a side of the box and a carboy therein, said means comprising an abutment member adapted to be placed into a corner of the box and a wedge element co-operating with the abutment member.

4. In a carboy box, the combination of a vertical strip carrying cushioning means in one face thereof to bear upon a carboy and wedging means for moving the strip in the box to force the cushioning means into firm engagement with the carboy.

5. In a carboy box, the combination of a plurality of vertical strips carrying cushioning means in one face and means for moving at least two of the strips from one of the corners of the box into the narrowing spaces between the adjacent sides of the box and the carboy therein.

6. In a carboy box, the combination of eight vertical strips carrying cushioning means in one face to bear upon a carboy and means for moving at least two of the strips from one of the corners into the narrowing spaces between the adjacent sides of the box and the carboy therein.

7. In a rectangular carboy box, a vertical strip having a flat surface to contact with a side of the box and cushioning members secured upon the opposite face of the strip at such an angle to the said contacting surface that pressure is exerted upon the carboy in a substantially radial direction when the strip is forced into one of the narrowing spaces between a side of the box and the carboy.

8. A strip according to claim 7 in which

the cushioning members are secured in recesses in the strip.

9. The method of supporting a carboy in a box, which consists in disposing a plurality of cushioning means around the carboy between the latter and the sides of the box and forcing at least two of the cushion-

ing means from one corner into the narrowing spaces between the adjacent sides of the box and the carboy to place them ¹⁰ under compression between the carboy and the sides respectively.

In testimony whereof, I affix my signature.
JOHN THOMAS SMITH.
